Primary Examiner—Carmen H. Vales-Lado[57] **CLAIM**

The ornamental design for a work stand for bicycles, as shown and described.

DESCRIPTION

FIG. 1 is an enlarged broken away front perspective view of the arm of the work stand for bicycles showing our new design;

FIG. 2 is a front elevational view thereof;

FIG. 3 is a side elevational view thereof from one side; the elevational view from the opposite side is a mirror image;

FIG. 4 is a rear elevational view thereof;

FIG. 5 is a top plan view thereof;

FIG. 6 is a bottom plan view thereof;

FIG. 7 is the front perspective view of the work stand for bicycles;

FIG. 8 is the front elevational view of the work stand for bicycles;

FIG. 9 is the left side elevational view thereof;

FIG. 10 is the right side elevational view thereof;

FIG. 11 is the rear elevational view thereof;

FIG. 12 is the top plan view thereof; and,

FIG. 13 is the bottom plan view of the work stand for bicycles.
